UNITED STATES PATENT OFFICE.

WILLIAM J. SMITH, OF NEW YORK, N. Y.

DESIGN FOR A NECKTIE-FRAME.

SPECIFICATION forming part of Design No. 30,176, dated February 14, 1899.

Application filed January 17, 1899. Serial No. 702,461. Term of patent 7 years.

To all whom it may concern:

Be it known that I, WILLIAM J. SMITH, of the city of New York, (borough of Brooklyn,) in the county of Kings and State of New York, have invented and produced a new and original Design for a Necktie-Frame, of which the following is a full, clear, and exact specification.

Reference is to be had to the accompanying drawings, forming a part of this specification, in which similar characters of reference indicate corresponding parts in both the views.

Figure 1 is a perspective view of a necktie-frame, showing my design; and Fig. 2 is a plan view of the same.

The design in its entirety consists of an approximately lozenge-shaped and forwardly-

curved front A, having an opening A' at the middle and upwardly-extending arms B at the sides of the front, said arms having their bases B' extending from the lower edge of the front at the sides thereof, as plainly indicated in the drawings.

The leading feature of the design consists of the front A and the arms B, rising at the sides of the front.

I claim—

The design for a necktie-frame, herein shown and described.

WILLIAM J. SMITH.
